(57) **CLAIM**

The ornamental design for an antenna, as shown and described.

DESCRIPTION

FIG. 1 is a top plan view of an antenna with a base in broken lines.

FIG. 2 is a side elevation view of the antenna of FIG. 1 with a base in broken lines.

FIG. 3 is a top perspective view of the antenna of FIG. 1 with a base in broken lines.

FIG. 4 is an isolated top perspective view of a small antenna element of the antenna of FIG. 1.

FIG. 5 is an isolated side elevation view of the small antenna element of FIG. 4.

FIG. 6 is an isolated front elevation view of the small antenna element of FIG. 4.

FIG. 7 is an isolated bottom plan view of the small antenna element of FIG. 4.

FIG. 8 is an isolated top perspective view of a large antenna element of the antenna of FIG. 1.

FIG. 9 is an isolated side elevation view of the large antenna element of FIG. 8.

FIG. 10 is an isolated front elevation view of the large antenna element of FIG. 8; and,

FIG. 11 is an isolated bottom plan view of the large antenna element of FIG. 8.

The broken lines are for illustration purposes only and form no part of the claimed invention.
